TOY BEAD LOOM

Frederick Wehrli, New York, N. Y.

Application June 25, 1951, Serial No. 233,473

6 Claims. (Cl. 28—15)

1

This invention relates to a toy loom for making beaded articles such as beaded belts, bands, necklaces and the like.

It is an object of my invention to provide a toy bead loom which is sturdy, rigid, simple in construction, and which can be easily adjusted and operated. The frame of the loom is formed of a single wire having its ends joined together to form a continuous loop. The loop is substantially rectangular in shape, the central portion of the loop forming a base and the two ends of the loop being bent upwardly. The upwardly bent ends are provided with thread spacing members. At a midpoint of the base portion, a loop bend is formed in the wire at each side of the base. The loop bends extend upwardly for supporting an axle therebetween. A pair of rollers are mounted on the axle with their adjacent ends abutting each other. The threads extend from a thread holding member on one of the rolls over the two thread spacing members and are then anchored or fastened to a member on the other roll. By turning the rolls the threads can be made taut, or they can be fed over the thread spacing members.

The invention will be more readily understood from the following description and the drawing, in which:

Fig. 1 shows a side view of one embodiment of my invention,

Fig. 2 shows a top view of the bead loom, and

Figs. 3 and 4 are sectional views of details.

Reference is made to Figs. 1 and 2 illustrating one embodiment of my invention. The loom includes a wire frame 1 formed of a wire of sufficient thickness to provide the requisite rigidity for the loom. The ends of the wire 1 are joined together, as by welding, to form a continuous loop substantially rectangular in shape. The rectangular loop is bent upwardly at the points 2 and 3 to provide a base portion 4 and a pair of upwardly extending ends 5 and 6 which have a certain amount of resiliency which helps to maintain the threads 21 taut. The base portion of the loop consists primarily of two sides 7 and 8 joined together by the upwardly extending ends 5 and 6. The base portion 4 is made rigid in a manner to be explained later. On the horizontal arms 9 and 10 of the ends 5 and 6 there are provided a series of grooves for holding the threads 21 properly spaced. The thread spacing grooves may be provided by springs 11 and 12 mounted on the horizontal arms 9 and 10. The springs 11 and 12 are placed on the wire 1

2

before the ends of wire 1 are joined together, and the springs are sufficiently flexible to permit them to be moved along wire 1 into their proper positions.

The base portion 4 of the wire frame is provided with means for supporting a pair of rolls 13 and 14. Rolls 13 and 14 have thread fastening or anchoring devices 15 and 16, respectively. Rolls 13 and 14 may be made of wood or any other suitable material, and the thread fastening devices 15 and 16 may be nails or screws. Rolls 13 and 14 preferably are unequal in length. The roll 13 may be made approximately two to four times as long as roll 14. The roll 13 is thus made wide enough to permit a wide beaded band to be rolled up thereon. The rolls 13 and 14 are supported above the base portion 4 on an axle 17, which may be a long machine screw. The axle 17 is mounted in a pair of loop bends formed in the sides 7 and 8 of the base portion 4. A wing nut 20 is provided for clamping rolls 13 and 14 together so that rotation of one roll will cause the other to rotate. Further tightening of the wing nut 20 will clamp the rolls 13 and 14 against the loop ends 18 and 19 tightly enough to prevent rotation of the rolls. The rolls 13 and 14 and the axle 17 maintain the spacing between sides 7 and 8 and thus render the base of the loom rigid.

The general mode of operation of toy bead looms of the type herein disclosed is well known in the art. A number of threads are fastened at one end to the fastening device 15 on roll 13. The threads are then fed through adjacent grooves of the spring or spacing member 12, and then through adjacent grooves of the other spacing member 11. After being pulled tight the threads are anchored or fastened to the fastening device 16 on the roll 14. After the loom has been properly threaded the threads 21 can be made taut by turning rolls 13 and 14 together, or by turning roll 14 with respect to roll 13. The wing nut 20 is then tightened to prevent further rotation of rolls 13 and 14. If it is desired to feed the threads 21 through the grooved members 11 and 12, the winged nut is loosened sufficiently to permit rolls 13 and 14 to rotate together to thereby unroll the threads from roll 14 and simultaneously roll up the threads or beaded band on roll 13. The threads 21 form the warp of the beaded article. The beads are threaded or woven on to warp threads 21 by a woof thread 22. One end of the woof thread is tied to one of the warp threads as at a point 24. The woof thread 22 is fastened to a needle 23 and beads 25 are

then placed on thread 22. The number of beads placed on the woof thread 22 at one time may equal the number of spaces between threads 21. Thread 22 is placed across threads 21 so that one bead lies in each space between threads 21. The woof thread 22 may then be looped around the last of the threads 21, and then again passed through the holes of the beads by means of the needle 23. This mode of operation is given merely as one illustration, it being evident that the beads may be woven or threaded in other manners.

It will be evident that I have provided a toy bead loom which is simple and durable in construction and in which the base of the frame is given additional rigidity by the rolls placed centrally thereof. The operation of the bead loom has been simplified by the reduction of the number of component elements and by arranging the rolls so that they can be turned together, and released for rotation or fastened against rotation by a single adjustment. It will be evident to those skilled in the art that a number of modifications and variations of the single embodiment of my invention disclosed herein may be made without departing from the scope of my invention as defined in the following claims:

I claim:

1. A toy loom comprising a frame having a substantially rectangular base and bent-up ends, a member having a series of grooves mounted on each bent-up end of the frame, an axle, a pair of rolls mounted adjacent each other on said axle, and a pair of members extending upwardly from opposite sides of said base for supporting said axle and rolls above said base.

2. A toy bead loom comprising a wire frame consisting of a single wire having its ends joined to form a loop having a flat base and bent-up ends, a series of grooves on each bent-up end of the loop, a pair of upwardly-extending axle-supporting members on said base opposite each other, an axle extending between said members, and a pair of rolls rotatably mounted on said axle.

3. A toy bead loom as defined in claim 2, in which each of the axle-supporting members consists of a loop formed in said wire at an intermediate point of said base.

5. 4. A toy bead loom as defined in claim 2, including means mounted on said axle for holding the adjacent ends of said rolls in engagement for causing rotation of one roll to rotate the other roll and for clamping said rolls on said axle to prevent rotation.

10 5. A toy bead loom as defined in claim 2, in which one of said rolls is appreciably longer than the other roll.

15 6. A toy bead loom comprising a wire frame consisting of a single wire having its ends joined to form a substantially rectangular continuous loop, the ends of the loop being upwardly bent from a base portion of the loop, a series of grooves extending across each of said upwardly bent ends, 20 a pair of upwardly extending loop bends in said wire at oppositely disposed points of said base portion, an axle extending through said loop bends, a pair of rolls of unequal length mounted on said axle, and means mounted on said axle 25 for holding the adjacent ends of said rolls in engagement for causing rotation of one roll to rotate the other roll and for clamping said rolls to prevent rotation thereof.

FREDERICK WEHRLI.
